UNITED STATES PATENT OFFICE.

WILLIAM A. GEIGER, OF CHICAGO, ILLINOIS, ASSIGNOR TO WILLIAM H. MINER, OF CHAZY, NEW YORK.

ADJUSTABLE SIDE BEARING.

1,149,361.

Specification of Letters Patent.

Patented Aug. 10, 1915.

Application filed October 22, 1914. Serial No. 867,991.

To all whom it may concern:

Be it known that I, WILLIAM A. GEIGER, a citizen of the United States, residing at Chicago, in the county of Cook and State 5 of Illinois, have invented a certain new and useful Improvement in Adjustable Side Bearings, of which the following is a full, clear, concise, and exact description, reference being had to the accompanying drawings, forming a part of this specification.

This invention relates to improvements in adjustable side bearings.

An object of the invention is to provide an adjustable bearing plate of a side bearing 15 for railway cars of simple construction and readily adjustable to any desired height.

The invention furthermore consists in the improvements in the parts and devices and in the novel combination of the parts and 20 devices, as herein shown, described or claimed.

In the drawing forming a part of this specification, Figure 1 is an end elevation of a body bolster and a truck bolster showing 25 my improvements in connection therewith. Fig. 2 is a vertical sectional view taken on the line 2—2 of Fig. 1 upon an enlarged scale. Fig. 3 is a sectional view taken on the line 3—3 of Fig. 2 and Fig. 4 is a broken 30 detail view illustrating another embodiment of my invention.

In said drawings, and referring to Figs. 1 to 3 inclusive, 10 denotes the body bolster and 11 a truck bolster, which may be of any 35 usual or well known design and having provided therebetween a side bearing on each side of the king pin. As shown, each side bearing comprises a lower member A and an upper member B. The member A consists 40 of a base bracket 12 having a cradle 13 rockably mounted therein, in which cradle is rotatably mounted an antifriction roller 14, the axis of the roller being at right angles to the pivotal axis of the rocking cradle. 45 The member B, which I have shown as attached to the under side of the body bolster, comprises a bearing block 15 having a lower flat bearing face 16 and upper, oppositely inclined faces 17—17. Each of the faces 17 50 is provided with an under cut groove 18, in which is adapted to slide back and forth a correspondingly shaped tongue 19 formed on a lower inclined side of an adjusting block 20, there being two of said blocks 20,

as clearly appears from Fig. 2. Each of 55 the adjusting blocks 20 is supported by a screw 21—21, one of which is threaded right hand and the other left hand and, as shown in Fig. 2, are conveniently formed in a single member. The screws 21 are swiveled 60 in the side walls 22—22 of the body bolster and means are provided for rotating said screws in the form of a disk 23 securely attached thereto, said disk 23 extending up through an opening 24 in the top wall of 65 the body bolster whereby the same may be rotated by means of a tool inserted in any one of the plurality of radially arranged holes 25 around the circumference thereof. To hold the disk 23 in any of its adjusted 70 positions, I provide a plurality of transversely extending holes 26 so located that they rise above the top wall of the body bolster and through which may be inserted a cotter 27. The bearing block 15 and the 75 adjusting blocks 20 are guided in their up and down movements by means of parallelly arranged walls 28, preferably cast integrally with the body bolster, see Fig. 3.

From the preceding description it will be 80 seen that by rotating the disk 23 in the desired direction, the bearing block 15 may be raised or lowered to the desired height relative to the surface of the friction roller 14 and thus compensate for any variations in 85 distance between the bolsters or wear on the parts.

In the structure shown in Fig. 4 the adjusting blocks 120 are each provided on their end face with a recess 30 and groove 90 31 into which is adapted to take and swivel the head end 32 of an adjusting screw 33, the latter being threaded in the side wall 22 of the body bolster and provided with a set nut 34 to retain it in any adjusted 95 position. Fig. 4 shows only one of the adjusting screws and adjusting block but, as will be understood, the opposite end is similar in arrangement and the bearing block 115 can be adjusted by turning the adjusting 100 screws 33—33.

I claim:

1. In an adjustable side bearing for railway cars, the combination with a bearing block having a lower flat bearing face and 105 upper, oppositely inclined faces, of adjusting blocks having lower inclined faces co-operating with the inclined faces of the

bearing block, the inclined faces having interfitting tongues and grooves whereby the adjusting blocks support the bearing block, and means for moving said adjusting blocks 5 inwardly and outwardly to thereby raise the bearing block.

2. In an adjustable side bearing for railway cars, the combination with a bearing block having a lower flat bearing face and 10 upper, oppositely inclined faces, of adjusting blocks having lower inclined faces co-operating with the inclined faces of the bearing block, the inclined faces having interfitting tongues and grooves whereby the adjusting blocks support the bearing block, and means for moving said adjusting blocks 15 inwardly and outwardly to thereby raise the bearing block, said means including an ad-

justing screw coöperable with each of said blocks.

3. In a device of the character described, the combination with a bolster having a pocket formed therein, the side walls of which are parallel, of a pair of adjusting blocks mounted in said pocket and slidable 25 back and forth therein and guided by said parallel walls, of a bearing block adjustably secured to the ends of said adjusting blocks, and adjusting screws for said adjusting blocks for moving the same toward and from 30 each other.

WILLIAM A. GEIGER.
